(57) CLAIM

The ornamental design for a bag holder, as shown and described.

DESCRIPTION

FIG. 1 is a perspective view of the bag holder;
FIG. 2 is a perspective view of the bag holder holding a bag;
FIG. 3 is a front elevation view of the bag holder holding a bag; and,
FIG. 4 is a side elevation view of the bag holder holding a bag.
The broken line showing of a bag is included for the purpose of illustrating environment and forms no part of the claimed design.
